George Eli Mongeau,
BY Albert M. Moore,
His ATTORNEY.

UNITED STATES PATENT OFFICE.

GEORGE ELI MONGEAU, OF LOWELL, MASSACHUSETTS.

GUARD FOR OUTSOLE AND WELT STITCHING MACHINES.

1,112,152.

Specification of Letters Patent. Patented Sept. 29, 1914.

Application filed February 16, 1911. Serial No. 608,999.

To all whom it may concern:

Be it known that I, GEORGE ELI MONGEAU, a citizen of the United States, residing at Lowell, in the county of Middlesex and 5 Commonwealth of Massachusetts, have invented a certain new and useful Improvement in Guards for Outsole and Welt Stitching Machines, of which the following is a specification.

10 This invention relates to guards for outsole and welt stitching machines used in the manufacture and repairing of boots and shoes and is particularly useful in the repair work of small shops, where frequently 15 the workmen are less skilful than those employed in large shoe-factories.

The machines referred to use two threads, one of which is drawn up by the needle through a hole in the work resting on a table 20 and through a slot or throat in said table, the hole in the work being previously made by an awl which passes up through said throat. The table in many cases has a very slight vertical thickness and in pressing the 25 welt against a gage, with which the machine is provided above the table, the upper is likely to project under said table and to be pierced by the needle or by the awl, or, if not so pierced, to be scratched or marked in 30 such a manner as to injure the appearance of the finished shoe, and a similar injury is likely to be caused while stitching the outsole to the welt.

The end of the table which points in the 35 direction opposite to that in which the work travels while being stitched, is sharp and frequently catches under the toe-cap (where such is used) of the shoe being operated on and interferes with the feed, seriously injuring the shoe or breaking the awl which 40 not only makes the hole through the leather but also feeds the work.

The object of this invention is to prevent such piercing and marking the upper below 45 the table and this without the necessity of fitting the sole on a last while attaching the out-sole to the welt; to enable an inexperienced operator to stitch closer to the upper, when necessary, without increasing the liability of the upper being caught by the awl 50 or needle below the table and without risk of piercing his fingers and to prevent the point of the table from catching the toe-cap.

This device does not interfere with the 55 threading of the looper or lower thread-guide and need not be removed for that pur-

pose. Said device may be used on a variety of shoe-sewing machines but is herein represented as attached to what is known to the trade as the "Goodyear outsole lock-stitch machine".

In the accompanying drawing, Figure 1 is a front elevation of such parts of a shoe-sewing machine as is necessary to the understanding of my invention, showing said invention attached to the edge-gage; Fig. 2, a right side elevation of said invention with the edge-gage and adjacent parts; Fig. 3, a left side elevation of a part of the frame, the table, a vertical cross-section of a part 70 of a shoe to which the out-sole is being sewed, the edge-gage, awl and needle and the upper end of my improved guard interposed between the table and the shoe-upper; Fig. 4, a left side elevation of the 75 guard detached; Fig. 5, a plan of the guard and part of the table; Fig. 6, a horizontal section on the line 6-6 in Fig. 1 of the guard and edge-gage.

A indicates a part of the frame of the 80 machine; B, the table which supports the work; C, the edge-gage supported upon a stand c which is adjustable to vary the distance of the stitches from the upper; D, the presser-foot; d, its holder; E, the awl; 85 F, the needle; S, the upper of a shoe; s, the welt; s¹, the insole; s², the out-sole; all these parts being of the usual construction and operation.

In sewing shoes on such a machine as this 90 invention relates to, the parts are inverted and in sewing the out-sole to the welt, the projecting part of the welt rests upon the table B.

To protect the fingers and the uppers of 95 shoes being operated upon, I use a guard G. This guard is formed of metal or material capable of resisting the friction and wear of the shoe-upper upon said guard, preferably of hard, spring sheet-steel and 100 the upper portion or head g of said guard extends for some distance along the front of the table beyond the ends of the slot b of said table in both directions, said slot b being a passage for the awl and needle and 105 the threads. The upper edge g¹ of the guard G is very thin in order not to materially increase the minimum distance of the row of stitches from the shoe upper, and closely fits the front of the table B but 110 does not rise above the top of the table except at the right end of said table which

is rounded or pointed at b^1 , as shown in Figs. 1 and 5, in the usual manner where the right end or front end of the head of said guard is bent backward and shaped 5 to form an incline g^2 to cover the pointed free end of said table and prevent the toe-cap of the shoe from being caught by said pointed end.

The edge against which the work first 10 comes, the right edge in Fig. 1 is bent backward below the incline g^2 at g^3 to hold and guide the work out of contact with a shank of the edge-gage C and the opposite side of said guard is cut away below the table in 15 such a manner as to admit the fingers to thread the machine in the usual manner, but not sufficiently to allow the fingers to get into the paths of the awl and needle. The guard is provided with a shank g^5 or 20 part adapted to be secured to a convenient part of the machine and is here represented as extending downward and as being secured by the lower screw c^1 which secures said edge-gage to the stand c, said screw 25 passing in the usual manner through said gage into said stand. The edge-gage is commonly adjustable to vary the distance between said gage and the path of the awl to vary the distance of the row of stitches 30 from the edge of the out-sole and the welt and where the guard is attached as above described, the guard being made of slightly elastic material allows the edge-gage to be adjusted in a backward and forward 35 direction without drawing the head of the guard out of contact with the table or to bring the edge g^3 of said guard out of contact with the adjustable edge-gage.

Although the guard might be attached to 40 any rigid part of the sewing machine conveniently placed for that purpose it is preferred to secure it as above described to the edge-gage. The guard is bulged at g^4 to

allow said guard to fit the shank of the edge-gage closely over another screw c^2 , Fig. 45 6, commonly used to secure the gage C to a stand c. The lower end of the guard is provided with an angle projection g^6 which fits the side of the shank of the edge-gage and prevents it from being turned by the 50 friction of the work thereon.

I claim as my invention:—

1. A guard adapted to be secured to a shoe-sewing machine in contact with the work supporting table thereof and to extend below said table and having an incline to extend over the work receiving end of said table. 55

2. The combination in a shoe-sewing machine with a work-supporting table having a work-receiving end, of an elastic guard adapted to press against said work-supporting table and reaching below said table in front of the awl and needle of said machine and having an incline extending over said 65 end of said table, to direct work in front of and upon said table, and means for supporting said guard.

3. A guard of elastic sheet metal adapted to be secured to the adjustable edge-gage of 70 a shoe-sewing machine and to press against the work-supporting table of said machine and reaching below said table and arranged in front of the awl and needle of said machine and having an incline extending over 75 the work-receiving end of said table to direct work in front of and upon said table, and having the edge of said guard on the side from which the work approaches bent backward to fit said adjustable edge-gage. 80

In witness whereof, I have affixed my signature in presence of two witnesses.

GEO. ELI MONGEAU.
